Primary Examiner — Robin V Webster*Assistant Examiner* — Rachel Voorhies*(74) Attorney, Agent, or Firm* — Pierson IP, PLLC(57) **CLAIM**

The ornamental design for a coffee pod storage device, as shown and described.

DESCRIPTION

FIG. 1 is a perspective view of a coffee pod storage device showing our new design thereof;

FIG. 2 is a top view of the coffee pod storage device shown in FIG. 1;

FIG. 3 is a bottom side view of the coffee pod storage device shown in FIG. 1;

FIG. 4 is a front view of the coffee pod storage device shown in FIG. 1;

FIG. 5 is a back view of the coffee pod storage device shown in FIG. 1;

FIG. 6 is a side view of the coffee pod storage device shown in FIG. 1; and,

FIG. 7 is a side view of the coffee pod storage device shown in FIG. 1.
